suitable cloths being interposed as found desirable. The band is then placed in the box A with its top mat-plate resting against the drainage-plate E and its bottom mat-plate 5 resting on the flanges of the band H. The platen or division-plate of the box A below should come up against the bottom of the band H, and hold the latter from dropping down. When pressure is applied to the machine in 10 the usual manner, the oil-meal is pressed between the top and bottom mat-plates I, causing the oil to be extracted therefrom, said oil being forced out in two directions—viz., up through the openings u of the top-plate I into 15 the slots m of the drainage-plate E, from whence it is carried by the filling o to each side of the box and out through the passages n to the box below, and, second, down through the openings u of the bottom mat-plate I to the 20 platen or division-plate D of the box A below.

It will be observed that the transverse shallow grooves k register with the openings u of the bottom mat-plate, so that the oil will drop into the said grooves k, traverse the same until 25 they cross the first longitudinal groove j, enter the latter and pass along, and through the slots l of the platen D into the grooves g' and pockets h on the under side thereof. The oil as it accumulates in said grooves and pockets is allowed to work out through the front and rear ends of the platen into the gutter or trough c, from whence it is carried off in the manner before explained. When the oil has 30 been extracted, the pressure is relieved and 35 the various bands containing the dry oil cake removed in the manner explained.

It will be observed that the peculiar construction of the slots m of the drainage-plate E serves to hold the wool or other filling firmly 40 therein and prevent it from working out of place. It will also be seen that by means of the detachable side plates, F, the latter may be removed to withdraw the drainage-plate E for cleaning the same, as desired.

45 Our improvements are simple in construction, efficient in operation, and will prove of great utility for the purposes intended.

Having described our invention, we claim—

1. In an oil-press, the combination, with the 50 telescopic boxes, of drainage-plates attached to the same and provided with grooves or channels having hair, wool, or other filling to form conducts for the oil and hold the same from returning to the cake when pressure is relieved, as and for the purpose set forth.

2. In an oil-press, the herein-described drainage-plate, having hair, wool, or equivalent lining fitted in grooves or channels thereof to form conducts for the oil, as and for the purpose set forth.

3. In an oil-press, the combination, with the 55 telescopic boxes, of the drain-plate resting against the under side of the box, and the side plates or walls attached to the box for holding the drain-plate in position, but allowing its detachment at will, for the purpose set forth.

4. In an oil-press, the combination, with the

telescopic boxes, of the drain-plate and the side plates or walls for holding the plate in position, the top edge of the side plates or walls 7c being cut out to allow the oil to escape from the drain-plate back or in rear of the side walls, for the purpose set forth.

5. In an oil-press, the combination, with the telescopic boxes having depending walls, of the 75 drain-plate fitted between the walls, and the side plates secured to the depending walls and holding the drain-plate in position, for the purpose set forth.

6. In an oil-press, the combination, with the 8c telescopic boxes having depending walls which are fluted or cut out on their inner faces to form passages, of the drain-plate fitted between the walls, and the side plates secured to the said walls and holding the drain-plate in 85 position, the top edge of the side plates being cut out to allow the passage of the oil from the drain-plate, over the same, and through the passages formed in the depending walls, as and for the purpose set forth.

7. In an oil-press, the combination, with the telescopic boxes having a series of steam channels provided in the same, of the steam-inlet communicating with the first of the series and the steam-outlet with the last of the series, 95 whereby the steam delivered by the inlet will have a continuous circulation through all of the steam-channels and be finally discharged through the outlet, as and for the purpose set forth.

8. In an oil-press, the combination, with the telescopic boxes having a series of steam-channels provided in the same, the first channels having communication with the second at one end and the second with the third at the opposite end, and so on alternately through the entire series, of the steam-inlet connecting with the first channel and the steam outlet with the last, as and for the purpose set forth.

9. In an oil-press, the combination, with the 105 telescopic boxes having grooves or channels provided in the upper face thereof, which grooves or channels have free communication with each other at the ends, of a steam inlet and outlet and a division plate or platen secured over the boxes to form a tight cover for the steam channels or grooves, for the purpose set forth.

10. In an oil-press, the combination, with the 115 telescopic boxes, of the division plate or platen having deep grooves cut longitudinally thereof and shallow grooves running transversely and crossing the deep grooves, for the purpose set forth.

11. In an oil press, the combination, with the 125 telescopic boxes, of the division plate or platen having deep grooves cut longitudinally in its top face and shallow grooves running transversely and crossing the deep grooves, channels provided in the under side of the platen, 130 and slots cut through the longitudinal deep grooves, so as to allow communication with the grooves in the under side, for the purpose set forth.

12. In an oil-press, the combination, with the telescopic boxes, of the division plate or platen having grooves or channels cut in the under side thereof, grooves provided in the top face 5 of the platen, and slots cut through the top grooves, so as to allow communication with the grooves or channels in the under side, for the purpose set forth.

13. In an oil-press, the combination, with the 10 telescopic boxes, of the arm or cam working through a slot or opening of the same to remove the mat or band therefrom, for the purpose set forth.

14. In an oil-press, the combination, with the 15 telescopic boxes, of the arm or cam, the rock-shaft on which it is mounted, the connecting-bar, and the operating-lever, arranged and operating for the purpose set forth.

15. In an oil-press, the combination, with the 20 telescopic boxes, of the band for holding the meal in place while undergoing pressure, comprising a rectangular frame made solid at the corners, for the purpose set forth.

16. In an oil-press, the combination, with the 25 telescopic boxes, of the band for holding the meal, comprising a rectangular frame open at the top and bottom, flanges provided at the bottom, and a mat-plate supported on the flanges, for the purpose set forth.

30 17. In an oil-press, the combination, with the

telescopic boxes, of the band for holding the meal, mat-plates arranged within the same and provided with small slots or openings, and the platen or division-plate secured to the top of the box below and grooved or channeled to correspond with the slots or openings of the mat-plates, for the purpose set forth.

18. An oil-press comprising the following instrumentalities, to wit: the telescopic boxes, the drainage-plate having its grooves or channels filled with hair or wool, the supplemental side walls or plates to hold the drainage-plate in position and also allow the oil to flow in rear of the side walls, the steam-channels provided in the top face of the boxes, the platen 45 serving as a cover for the steam-channels and grooved to allow the flow of oil, the band for holding the meal, and the mat-plates working in the band, for the purpose set forth.

In testimony that we claim the foregoing as 50 our own we have hereto affixed our signatures in presence of two witnesses.
